UNITED STATES PATENT OFFICE.

RAY F. KUNS, OF CINCINNATI, OHIO.

DESIGN FOR A CHILD'S TOY VEHICLE.

54,933.

Specification for Design.

Patented Apr. 20, 1920.

Application filed September 15, 1919. Serial No. 324,049. Term of patent 14 years.

To all whom it may concern:

Be it known that I, RAY F. KUNS, a citizen of the United States, residing at Cincinnati, in the county of Hamilton and State of Ohio, have invented a new, original, and ornamental Design for Children's Toy Vehicles, of which the following is a specification, reference being had to the accompanying drawing, forming part thereof.

The figure is a perspective view of a child's toy vehicle, showing my new design.

I claim:

The ornamental design for a child's toy vehicle, as shown.

RAY F. KUNS.
